UNITED STATES PATENT OFFICE

160,194

CIGARETTE PACKAGE HOLDER

Lawrence Moss, New York, N. Y.

Application February 4, 1950, Serial No. 7,749

Term of patent 3½ years

(Cl. D85—2)

To all whom it may concern:

Be it known that I, Lawrence Moss, a citizen of the United States of America, residing in New York, county of New York, and State of New York, have invented a new, original, and ornamental Design for a Cigarette Package Holder, of which the following is a specification, reference being had to the accompanying drawing, forming part thereof.

Fig. 1 is a front perspective view of a cigarette package holder, showing my new design.

Fig. 2 is a rear perspective view thereof.

Fig. 3 is a side elevational view.

I claim:

The ornamental design for a cigarette package holder, substantially as shown.

LAWRENCE MOSS.
